UNITED STATES PATENT OFFICE.

SOLOMON LAZAR, OF SAN FRANCISCO, CALIFORNIA.

PAPER-FOLDING MACHINE.

1,132,731.

Specification of Letters Patent. Patented Dec. 29, 1914.

Application filed February 20, 1913. Serial No. 719,731.

To all whom it may concern:

Be it known that I, SOLOMON LAZAR, a citizen of the United States, residing in the city and county of San Francisco and State of California, have invented a new and useful Improvement in Paper-Folding Machines, of which the following is a specification.

My invention relates to an improved machine for folding and interleaving a plurality of paper strips wherein a plurality of overlapping, open dies are used to interleave, fold and guide said paper strips in the manner set forth and for the purpose described in Letters Patent Number 843,219, issued to Solomon Lazar and dated February 5th, 1907, and the objects of my invention are first, to provide means for supporting the upper as well as the lower dies throughout the length thereof, second, to provide open dies so that the threading of the paper strips through the machine may be greatly facilitated and simplified, and third, to provide a cheaper and more simple construction, and fourth, to reduce friction by reducing the superficial area of the dies.

For a full and clear comprehension of my invention, reference should be had to the drawings forming a part of this specification wherein like numerals of reference designate similar parts throughout the said specification and drawings and wherein—

Figure 1 is a plan view of the paper folding machine. Fig. 2 is a longitudinal section partly broken away and on a larger scale. Figs. 3, 4 and 5 are diagrammatic views disclosing the relative positions of the upper and lower dies and the manner in which both upper and lower dies are supported, at sections taken near the beginning, center and ends, respectively, of the dies. Fig. 6 is a broken detail view of one of the upper dies disclosing the manner in which the said die is supported throughout its length.

My improved paper folding machine consists substantially of a horizontal table 1 having an extension 2 at one end thereof with the pressure blocks 3, through which the interleaved paper strips are drawn, mounted thereon. A rectangular sleeve 4 is secured to the table 1 and is provided for the purpose of securing the interleaved ends of the open dies 5 and 6 which radiate from the said sleeve 4 into flat surfaces at the opposite ends thereof, which are secured to the

flared guides 5' and 6' respectively. The dies 5 and 6 are folded centrally and longitudinally so as to operate gradually to fold a strip of paper centrally and longitudinally when the said paper is passed over the said dies, as hereinafter described. The upper dies 6 are substantially convexed while the lower dies 5 are concaved. The lower dies 5 are supported in a straight horizontal position by the table 1. The upper dies 6 are supported throughout their length by the horizontal tapered supports 7 which rest on the table 1 and extend between the lower dies 5 and engage the approximate center of the upper dies 6 as illustrated in Figs. 3, 4 and 5 of the drawings. Strips of paper 8 and 9 are fed from suitably supported rolls through the flared guides 5' and 6' of the dies 5 and 6 respectively, and after passing over the said dies 5 and 6 and through the sleeve 4, are interleaved and folded in the usual manner. Heretofore the dies were composed of light, flexible material which, being supported only at intervals, would sag and bend under their own weight and cause the paper strips to be deflected to either side thus necessitating guides or closed tubes to prevent such deflection.

My improvement consists chiefly in open dies which are supported throughout the entire length thereof by means of the table 1 so as to provide substantially a straight path for the paper strips, to be interleaved and folded, from the flared guides 5' and 6' to the interleaving ends of the dies 5 and 6 respectively. Inasmuch as the supporting dies 5 and 6 are supported by the table 1 in practically a straight line, there is no tendency on the part of the said dies to deflect the paper strips to either side. Consequently the said strips are fed into the interleaving ends of the dies in an even manner and are folded and interleaved evenly.

The obvious advantages of my construction are, accessibility of the dies which facilitates the threading of the paper strips and eliminates the necessity for an emergency strip for re-threading purposes when one of the paper strips becomes detached or broken. The open dies also admit of a simple and cheap construction which is very essential in machines of this class. With open dies the superficial area is also greatly reduced, thus eliminating friction between the paper and the dies, consequently less power is required to draw the paper through the machine,

which reduces the tendency of the paper to break or tear.

Having thus described my invention, what I claim as new and desire to secure by Letters Patent is—

1. In a paper folding machine, the combination of an upper and a lower series of open dies, the dies of each series being bent lengthwise so as to operate gradually to fold a strip of paper centrally and longitudinally when the said strip is passed over the said dies, the dies of the lower series being substantially concaved and the dies of the upper series being substantially convexed in cross-section relative to the dies of the said lower series, the sides of the dies of the upper series fitting into the concavities of the lower series; and horizontally extending supports between each pair of dies of the lower series adapted to support the dies of the upper series.
2. In a paper folding machine, the combination of a suitable horizontal table; an upper and a lower series of open dies se-

cured to the said table, the dies of each series being bent lengthwise so as to operate gradually to fold a strip of paper centrally and longitudinally when the said strip is passed over the said dies, the dies of the lower series being substantially concaved and the dies of the upper series being substantially convexed in cross-section relative to the dies of the said lower series, the sides of the dies of the upper series fitting into the concavities of the lower series; and horizontally extending tapered supports secured to the horizontal table and between each pair of lower dies and adapted to support each upper die throughout the length thereof.

In witness hereof I hereunto set my signature in the presence of two subscribing witnesses.

SOLOMON LAZAR.
